The ornamental design for a motorcycle LED taillight with integrated turn signals, as shown and described.

DESCRIPTION

FIG. 1 is a rear perspective view of a motorcycle LED taillight with integrated turn signals, showing my new design;

FIG. 2 is an enlarged rear perspective view thereof;

FIG. 3 is a rear elevational view thereof;

FIG. 4 is a front elevational view thereof;

FIG. 5 is a right-side elevational view thereof;

FIG. 6 is a left-side elevational view thereof;

FIG. 7 is a top plan view thereof;

FIG. 8 is a bottom plan view thereof;

FIG. 9 is an enlorged perspective view of a first type of LED of the design, taken along line 9 of FIG. 2; and,

FIG. 10 is an enlorged perspective view of a second type of LED of the design, taken along line 10 of FIG. 2.

The broken lines showing a motorcycle and lamp enclosure in FIG. 1 depict environmental matter and form no part of the claimed design. The remaining broken lines depict portions of the motorcycle LED taillight with integrated turn signals that form no part of the claimed design.
